UNITED STATES PATENT OFFICE.

ALEXANDER D. STEWART AND EDGAR W. CLARKE, OF HAMILTON, ONTARIO, CANADA,
ASSIGNORS TO MERCURY MILLS, LIMITED, OF HAMILTON, PROVINCE OF ONTARIO,
CANADA.

KNITTING MACHINE.

Application filed October 30, 1924. Serial No. 746,865.

To all whom it may concern:

Be it known that we, ALEXANDER D. STEWART and EDGAR W. CLARKE, of the city of Hamilton, in the county of Wentworth, Province of Ontario, Canada, subjects of the King of Great Britain, have invented certain new and useful Improvements in Knitting Machines, of which the following is a specification.

10 This invention relates to knitting machines and more particularly to the circular type of knitting machines for automatically knitting ribbed hose, in which type upper and lower cylinders are provided and the 15 needles are transferable from one cylinder to the other as desired, whereby the hose may be partially knitted plain and with various widths of ribs. The general practice is to knit the heel, the toe and the sole portions of the hose plain, the instep, the leg 20 and the cuff being ribbed. In knitting silk hose the toe, heel, and cuff thereof are generally formed of stronger yarn such as cotton and usually these parts are reinforced 25 by feeding two yarns at the same time to the needles. In machines of the above type only one type of yarn can be positioned for feeding the needles at one time.

Heretofore it has been the practice to stop 30 the machine, when the desired point is reached to change the yarn, and manually break the yarn being fed to the needles and then tie the end of this yarn to the end of another yarn so that the new yarn will be 35 fed to the needles. The object of the present invention is to provide simple mechanism for automatically knotting the threads in machines of the above type.

We attain our object by means of the constructions hereinafter described and illustrated in the accompanying drawings in which—

Fig. 1 is a plan view of an automatic rib hose knitting machine showing the knotter and 40 yarn selecting mechanism thereon and the means for controlling the operation thereof;

Fig. 2 an end elevation thereof;

Fig. 3 an enlarged plan view of the knotter and yarn selecting mechanism;

Fig. 4 an end elevation of the same;

Fig. 5 a rear view of the same;

Fig. 6 a view similar to Fig. 4 showing

only the actuating parts for the knotter and 55 yarn selecting mechanism;

Fig. 7 a front view of some of the parts shown in Fig. 6;

Fig. 8 a rear view of the yarn selecting 60 mechanism; and

Fig. 9 a view illustrating one type of hose formed on the rib hose knitting machine.

1 is the frame of an ordinary circular automatic rib hose machine on which frame are suitably carried the upper and lower 65 needle cylinders 2 and 2^a, and the tray 3. A drive shaft 4 provided with a pulley 5 is adapted to rotate the cylinders. The pattern mechanism of this machine includes a pattern chain 6 mounted on a sprocket secured to the pattern shaft 7. In this type of machine the needles are transferable from one cylinder to the other which necessitates the 70 yarn being fed to the needles through a feed opening 8 formed in a suitable part and located substantially opposite the adjacent ends of the said cylinders. The above type of knitting machine is shown and described in Canadian Patent 161,697 and is well 75 known in the art.

These rib hose machines are adapted to knit a complete stocking and are therefore provided with means (not shown) for automatically changing the rotary motion of the needle cylinders into a rotary reciprocating 85 motion for knitting the heel and toe of the hose. As hereinbefore mentioned it is the usual custom to reinforce the heel and toe of the hose and when silk hose is being knitted a stronger and cheaper yarn is used in making the heel, toe and cuff of the hose. This 90 is illustrated in Fig. 9 of the drawings in which the cuff *c* is formed of two strands of cotton yarn, the leg portion *l* one strand of silk yarn, the heel *h* two cotton yarns, the sole and instep portions *s* and *i* respectively one silk yarn, and the toe *t* two cotton 95 yarns. To knit this particular hose it requires four changes in the yarns fed to the needles and heretofore these changes have been made by the operator, who had to break 100 the thread being fed to the needles and tie the new thread to the end thereof so that the old thread would feed the new thread through the feed opening 8 and thus to the needles. When knitting ribbed hose having a plurality of different colors, the colored

yarns have heretofore been also changed by the operator in the manner just described.

In Figs. 3 to 8 are shown a knotter and yarn selecting means, both being known in the art and therefore only briefly described. The knotter includes a bill hook K which is operated by suitable mechanism (not shown) from the lever K'. The said mechanism is provided with a cover K² and is suitably carried on a frame 9 carried on standards 10 secured to a base 11. This base is suitably secured to a bracket 12 which is secured to the rear side of the frame 1. The lever K' is fulcrumed at K³, see Fig. 3, and is adapted to actuate the jaws K⁴ which are adapted to grasp the thread being fed to the needles while the bill hook is tying a knot. A spring K⁵ tends to hold the lever K' in its inoperative position. An arm K⁶, having a pin and slot connection with the lever K', is secured to a vertical spindle K⁷ journaled in the frame 9 and bracket 12. At the lower end of this spindle is secured an arm K⁸ provided with an anti-friction roller, the purpose of which will hereinafter be described.

The yarn selecting means includes a plurality of movable yarn guiding fingers S', S², S⁴, each having a hole formed at its extremity, through which the yarns are led from the bobbins. The bobbin 13 shown in Fig. 2, carries the silk thread used for the portions *l*, *i* and *s* of the hose and this thread is led through the guide finger S'. Each of the bobbins 14 carries a cotton yarn for knitting the portions *c*, *h* and *t* of the hose, both yarns being led through the guide finger S². To make the hose hereinbefore described, which is of the simplest type, it only requires two of the guide fingers being used, but with other styles of hose it may be necessary to use all the fingers and if desired more fingers could be added, each finger carrying a different quality or color of yarn from its bobbin. The threads passing through the guide fingers are passed between fixed guide plates S⁵ and S⁶ which are suitably carried by the frame 9, see Figs. 4 and 5. The thread or threads running to the feed opening 8 are passed through the guide 15, the spring tension guide 16 and any desired number of other guides suitably positioned to lead the thread to the said opening as shown in Fig. 2. The end of each inactive thread is held by means of a clamp indicated at S⁷ in Fig. 4. This clamp is also known in the art and therefore not shown in detail and is hereinafter briefly described.

A swinging arm S⁸ carried on a bevel pinion S⁹ meshing with teeth formed in the side of a disk S¹⁰ is adapted to carry an inactive yarn or yarns passing through any one of the yarn guiding fingers together with the yarn or yarns feeding the needles, to the knotter. The disk S¹⁰ is secured to a shaft S¹¹ and is connected by a link S¹² with

an arm S¹³ loosely mounted on a spindle S¹⁴. This arm is adapted to be swung upwardly, as hereinafter described, to raise the link S¹² to the position shown in dotted lines in Fig. 6 and thus partially rotate the disk S¹⁰. 70

The yarn guiding fingers S', S², S³ and S⁴ are pivotally mounted on a spindle S¹⁵ and are normally positioned by springs S¹⁶ as shown in full lines in Fig. 6. A sector S¹⁷ slidably and rotatably mounted on the shaft 75 S¹¹ is adapted to engage any one of the fingers to depress it to the position indicated in dotted lines in Fig. 6. The sector is rotarily moved by means of a pin S¹⁸ carried by the disk S¹⁰, which pin passes through the 80 sector and is eccentric to the shaft S¹¹. The sector is moved axially of the shaft S¹¹ by means of an arm S¹⁹ which engages a groove formed in a collar S²⁰ formed on or secured to the sector. This arm is secured to a 85 spindle S²¹ axially movable in the frame 9 and is provided with a pin S²² adapted to be received in a cam slot formed in a cam 90 S²³ secured to one arm of a bell crank S²⁴ fulcrumed on the shaft S¹¹. This pin and 95 slot connection is so arranged that the sector may be positioned over any one of the yarn guiding fingers depending on the amount of rotary movement imparted to the bell crank S²⁴. The other arm of the latter is connected 100 by a link S²⁵ with an arm S²⁶ loosely mounted on the spindle S¹⁴. This arm is connected by means of a pin S²⁷ with a cam S²⁸ having high and low portions, formed on its cam surface, adapted to engage a pawl S²⁹ suitably carried on the arm S¹³. A spring S³⁰ tends to position the bell crank so that the sector is normally in engagement with the finger S' and the pawl S²⁹ in engagement with the high portion of the cam S²⁸. A dog 105 S³¹, carried by an arm S³², pivoted on the spindle S¹⁴, is adapted to engage the pawl S²⁹ when the cam S²⁸ has been rotarily moved to bring the pawl into engagement with the low surface thereof. 110

To actuate the arm K⁸ for operating the knotter and to actuate the dog S³¹ for operating the selecting means, we provide a shaft 17 journaled in the bracket 12 and in a bearing 18 secured to the frame 1. This shaft is driven by gearing 19 from the drive shaft 4 and is provided with an eccentric S³³ suitably connected with the arm S³² so that the latter, and thus the dog S³¹, are constantly oscillated when the machine is in 115 motion. The gear 19 is provided with a cam 20 adapted to engage the anti-friction roller on the end of the arm K⁸. Normally this roller is held out of engagement with the cam by means of a lateral projection K⁹, 120 secured to the spindle K⁷, and adapted to rest on the periphery of the sector S¹⁷. When the latter is rotated, as hereinbefore described, the projection is lowered until the arm K⁸ engages the top of the frame 9, this 125 130

lowers the anti-friction roller into the path of the cam 20.

To control the operation of the knotter and the selecting mechanism, auxiliary pattern mechanism is provided. This mechanism includes a pattern shaft 21 journaled in the bracket 12 and bearing 18. To this shaft is secured a ratchet wheel 22 having one or more blank teeth 22^a formed thereon. A pawl 23 suitably carried by the eccentric strap of an eccentric 24 normally travels across one of the blank teeth 22^a and is adapted to pick the ratchet wheel to rotate the shaft 21 and thus a sprocket 25 secured thereto. This sprocket carries an auxiliary pattern sprocket chain 26 having a plurality of projections 27 and 27^a formed on or secured thereto. These projections are adapted to engage an anti-friction roller carried on a lever 28 pivoted on the bearing 18 and having a pin and slot connection with the first mentioned arm of the bell crank lever S²⁴. It will be noted that the projections 27 and 27^a are of different heights so that the amount of movement imparted to the lever 28 and thus the bell crank will be varied to vary the position of the selector S¹⁷. It will be understood that a projection will be provided on the auxiliary pattern chain for each yarn guiding finger in use.

To control the operation of the ratchet wheel 22 we provide the following means. A lever 29 pivoted intermediate its ends on lugs 30 secured to the underside of the tray 3 is adapted to be engaged by projections 31 formed on or secured to the links of the primary pattern chain 6. The opposite end of the lever 29 is provided with a pawl 32 adapted to engage the ratchet wheel 22 whereby the latter will be partially rotated when the lever is engaged by one of the projections 31. This movement of the ratchet wheel is sufficient to permit the constantly operated pawl 23 to engage the normal teeth on the ratchet wheel and thus rotate the latter until the pawl engages the next blank tooth 22^a. While the ratchet wheel is being picked the auxiliary pattern chain 26 is also being driven to cause one of the projections thereon to engage the roller on the lever 28 to actuate it as hereinbefore described.

Assuming a stocking has just been finished and the cotton yarns from the bobbins 14 are being fed through the finger S², between the guide plates S⁵ and S⁶, through the guide 15 and spring tension guide 16 to the feed opening 8 and then to the needles, the mode of operation to knit the hose shown in Fig. 9 is as follows. The silk yarn from the bobbin 13 is led through its finger S', between the plates S⁵ and S⁶ and the end thereof held in the clamp S⁷. The cuff c is then knitted and when the desired

point for starting the leg portion 7 is reached one of the projections 31 engages the lever 29 to cause the pawl 32 to move the ratchet wheel 22 and thus permit the constantly operated pawl 23 to pick it. The intermittent motion thus imparted to the shaft 21 causes the sprocket 25 to rotate the auxiliary pattern chain 26 and thus causes the projection 27 to rock the lever 28 which rocks the bell crank S²⁴. It will be noted that the slot in the cam S²³ first extends at right angles to the axis of the spindle S²¹ and is then inclined to the said axis. This enables the cam to be slightly moved with the bell crank without shifting the sector S¹⁷, the slight movement of the bell crank being necessary to cause the high portion of the cam S²³ to be moved out of engagement with the pawl S²⁹. The constantly operated dog S³¹ then engages the pawl S²⁹ and pushes it up together with its arm S¹³ which causes the link S¹² to partly rotate the disk S¹⁰. This disk causes the rotation of the sector S¹⁷ which depresses the yarn guiding finger S' to bring the silk thread into the path of the swinging arm S⁸ as indicated in dotted lines in Fig. 6. The disk S¹⁰ also causes the rotation of the arm S⁸ which is formed with a grooved end adapted to pick up the thread or threads in its path. This arm also engages the threads being fed to the needles and carries them around, with the inactive thread, to the bill hook K and the jaws K⁴. As the sector is rotated the projection K⁹ is lowered to bring the roller on the cam K⁸ into the path of the constantly rotating cam 20 which causes the knotter operating spindle K⁷ to be partly revolved to operate the knotter to tie the knot. The jaws K⁴ are also operated by this spindle to grasp the yarns to take the tension of the running threads off the bill hook and at the same time draw down the tension guide 16 which is adapted to provide sufficient slack in the running threads to permit the knot being tied. The knotter is also adapted to cut off the ends of the tied threads close to the knot. The knotter operating spindle K⁷ also causes the clamp S⁷ to engage the running threads below the bill hook and draw the ends of these threads into the clamp so that they can be positioned for engagement with the swinging arm when it is desired to use these threads again.

The disk S¹⁰ and thus all the parts of the selecting means and the knotter actuating arm K⁸ are returned to their normal positions by means of the dog S³¹. The upper end of this dog is adapted to engage an adjusting screw S³⁴ threaded in a lug formed on the arm S¹³, see Figs. 4 to 7. The angle silk thread is now carried to the needles by means of the old threads as shown in Figs. 4 and 5 and when the heel h is reached the cotton threads are substituted for the silk

thread which change is made in the same manner as the one just described except that the projection 27^a will move the lever 28 through a slightly longer arc than that caused by the projection 27 so that the sector spindle S²¹ will be axially moved to position the sector S¹⁷ over the finger S² which will cause this finger to be depressed to bring the cotton threads into the path of the swinging arm S⁸.

After the heel is knit the feeding yarn is changed again from cotton yarns to a silk yarn as described, and when the toe is reached the cotton yarns are substituted for the silk yarn. As the cuff of the hose is formed of cotton it will not be necessary to make any further changes in the knitting yarn until the leg portion l of the next hose is reached.

20 What we claim is:—

1. The combination in a circular knitting mechanism for knitting ribbed hose, of a pattern shaft having primary pattern mechanism mounted thereon; a knotter attachment including a plurality of movable yarn guiding fingers, a swinging arm adapted to carry threads to the knotter, and selecting means adapted to actuate any one of the fingers to position its thread in the path of the 25 yarn; a second pattern shaft; means for actuating the swinging arm and the selecting means; auxiliary pattern mechanism for controlling the actuating means carried on the second shaft; and means for actuating the auxiliary pattern mechanism controlled by the primary pattern mechanism.

2. The combination in a circular knitting machine for knitting ribbed hose, of a pattern shaft having primary pattern mechanism mounted thereon; a knotter attachment including a plurality of movable yarn guiding fingers, a swinging arm adapted to carry threads to the knotter, and selecting means adapted to actuate any one of the fingers to position its threads in the path of the arm; a second pattern shaft; means for actuating the swinging arm and the selecting means; auxiliary pattern mechanism for controlling the actuating means carried on the second shaft; and actuating means for the auxiliary pattern mechanism including a lever adapted to be engaged by the primary pattern mechanism to cause the auxiliary pattern mechanism actuating means to function.

3. The combination in a circular knitting machine for knitting ribbed hose, of a pattern shaft having primary pattern mechanism mounted thereon; a knotter attachment including a plurality of movable yarn guiding fingers, a swinging arm adapted to carry threads to the knotter, and selecting means adapted to actuate any one of the fingers to position its thread in the path of the arm; a second pattern shaft; means for actuating

the swinging arm and the selecting means; auxiliary pattern mechanism for controlling the actuating means carried on the second shaft; a ratchet wheel carried on the second shaft and adapted to drive the auxiliary pattern mechanism, the ratchet wheel having a blank tooth; a lever having one end in engagement with the primary pattern mechanism; constantly driven means adapted to pick the ratchet wheel and normally traveling across the blank tooth thereof; and a pawl carried on the end of the lever remote from the primary pattern mechanism and adapted to rock the ratchet wheel when the lever is rocked to permit the picking means to rotate the ratchet wheel.

4. The combination in a circular knitting machine for knitting ribbed hose, of a pattern shaft having primary pattern mechanism mounted thereon; a knotter attachment including a plurality of movable yarn guiding fingers, a swinging arm adapted to carry threads to the knotter, and selecting means adapted to actuate any one of the fingers to position its thread in the path of the arm; a second pattern shaft; means for actuating the knotter, the swinging arm and the selecting means; auxiliary pattern mechanism for controlling the actuating means carried on the second shaft; and means for actuating the auxiliary pattern mechanism controlled by the primary pattern mechanism.

5. The combination in a circular knitting machine for knitting ribbed hose, of a pattern shaft having primary pattern mechanism mounted thereon; a knotter adapted to join one thread to another; a drive shaft for the machine having a gear secured thereto; a pinion meshed with the gear and provided with a cam adapted to actuate the knotter; a second pattern shaft; means for controlling the operation of the knotter including auxiliary pattern mechanism and the latter being carried on the second pattern shaft; and means for actuating the auxiliary pattern mechanism controlled by the primary pattern mechanism.

6. The combination in a circular knitting machine for knitting ribbed hose, of a pattern shaft having primary pattern mechanism mounted thereon; a knotter attachment including a plurality of movable yarn guiding fingers, a swinging arm adapted to carry threads to the knotter, and selecting means adapted to engage any one of the fingers to position its thread in the path of the arm; a constantly driven cam adapted to actuate the knotter; a second shaft; means for actuating the swinging arm and the selecting means; auxiliary pattern mechanism carried on the second shaft for controlling the operation of the knotter and the said actuating means; and means for actuating the pattern mechanism controlled by the pattern means.

7. The combination in a circular knitting

machine for knitting ribbed hose, of a pattern shaft having primary pattern mechanism mounted thereon; a knotter attachment including a plurality of movable yarn guiding fingers, a swinging arm adapted to carry threads to the knotter, and selecting means adapted to engage any one of the fingers to position its thread in the path of the arm; a constantly driven cam adapted to actuate the knotter; a second shaft; means for actuating the swinging arm and the selecting means; auxiliary pattern mechanism carried on the second shaft for controlling the operation of the knotter and the said actuating means; and actuating means for the auxiliary pattern mechanism including a lever adapted to be engaged by the primary pattern mechanism to cause the auxiliary pattern mechanism actuating means to function.

20 8. The combination in a circular knitting

machine for knitting ribbed hose, of a pattern shaft having primary pattern mechanism mounted thereon; a knotter adapted to join one thread to another; means for guiding a plurality of yarns; means for selecting one of the yarns and carrying it, together with the yarn being fed to the knitting needles, to the knotter whereby the new yarn will be substituted for the old yarn and fed to the knitting needles; a second pattern shaft; auxiliary pattern mechanism carried on the second shaft for controlling the operation of the selecting and carrying means and the knotter; and means for actuating the auxiliary pattern mechanism controlled by the primary pattern mechanism.

Signed at Hamilton, this 3rd day of October, 1924.

ALEXANDER D. STEWART.
EDGAR W. CLARKE.
